UNITED STATES PATENT OFFICE.

GEORGE BOOTH, OF TORONTO, CANADA, ASSIGNOR TO THE TORONTO STEEL CLAD BATH AND METAL COMPANY, OF SAME PLACE.

BATH-TUB.

SPECIFICATION forming part of Letters Patent No. 601,236, dated March 29, 1898.

Application filed March 18, 1897. Serial No. 628,143. (No model.)

To all whom it may concern:

Be it known that I, GEORGE BOOTH, manufacturer, of the city of Toronto, in the county of York, in the Province of Ontario, Canada, 5 have invented certain new and useful Improvements in Bath-Tubs, of which the following is a specification.

My invention relates to improvements in enamel-lined bath-tubs; and the object of the 10 invention is to produce a light bath-tub which will absorb but a minimum amount of heat and thereby not have a tendency to cool hot water when used; and it consists, essentially, of a bath-tub made of sheet metal, preferably 15 in three sections, the sections being joined together by an overlapping form of joint, so arranged that the interior surface of the sheet metal at the joint is substantially flush and finished smooth without crack or crevice, and 20 the protuberance of the joint is formed, preferably, on the exterior of the bath-tub, the overlapping portions being preferably secured together by rivets countersunk on the inside of the bath-tub and finished smooth, 25 the whole interior of the bath having fixed upon it a lining of enamel or other vitreous material by which a smooth unbroken and unmarred surface covering the joints is given to the interior of the bath-tub, as hereinafter 30 more particularly explained.

Figure 1 is a longitudinal sectional perspective view of a bath-tub constructed in accordance with my invention before the enamel lining has been fused onto the metal.

35 Fig. 2 is a similar view of the bath-tub complete. Fig. 3 is an enlarged sectional view, exaggerated, showing the joints.

In the drawings like letters of reference indicate corresponding parts in each figure.

40 Heretofore bath-tubs have been made of cast-iron in one piece with a lining of enamel. Necessarily in this construction the iron had to be of such a weight and thickness that not only was it inconvenient for transportation, 45 but the thickness of the material was such that when hot water is used in the bath-tub the heat of the hot water would be absorbed by the material and the water thereby rendered cool and consequently useless to a person 50 wanting a hot bath.

I have already obtained a patent in the United States for a bath-tub with a lining of

aluminium, copper, or other light material. Although this is a light bath and possesses many advantages, yet it is difficult to keep 55 clean and of a presentable appearance.

In the present invention I have sought to obtain not only lightness, but to produce a bath-tub of which the interior may be always kept perfectly clean and present a smooth 60 unbroken surface not liable to be affected by the bathing-water.

A is the head, B the central, and C the foot section, of the bath-tub, which have upper terminal flanges a, b, and c, respectively. 65 The central section B is provided with end-depressed flanges b' and b'', extending lengthwise of the bath-tub. At the outer ends of the flanges b' and b'' are formed outwardly-turned lips b³ and b⁴, respectively. These 70 lips b³ and b⁴ serve to form a means of connecting the legs or supports C' of the bath-tub to it.

a' is an inturned flange extending lengthwise of the bath-tub and formed at the inner 75 edge of the head-section A, such inturned flange being designed to be secured to the flange b', preferably by rivets D, the inner ends of which have countersunk heads. The edge of the flange a' is brought against a 80 shoulder b⁵ of the depressed flange in such a manner that it may be hammered and wedged against it and thereby when finished off smooth by an emery-wheel present no projections or inequalities of surface liable to 85 interfere with the perfect enameling and use of the bath-tub after being enameled.

The foot-section is provided with an in-turned flange c', extending lengthwise of the bath-tub and designed to be fastened by rivets E upon the depressed flange b'' in a similar manner to that in which the flange a' is fastened to the depressed flange b'. The flange c' would also preferably be finished flush with the surface of the central section B. 95

Although I describe the flanges a' and c' being finished flush, it will of course be understood that they might be raised as long as no sharp corner would be formed liable to interfere with the proper enameling and use of 100 the bath-tub. Again, I may state that although I show rivets as securing the connecting-flanges of the central and head sections I might electrically weld these flanges together.

- The great object to be attained, however, is to prevent the joint at the bottom of the bath from gaping open during the great heat necessary for enameling, and this I find in practice is effectually prevented by having the broad overlapping joint hereinbefore described in which any tensile tendency is prevented by the broad abutting gripping-surfaces of the flanges when held tightly together. I have made several experiments on the joint and have found that this is the only joint which seems to withstand the effect of the firing during the process of enameling.
- I find outwardly-turned abutting flanges, as in my copper-lined sheet-metal bath-tub, entirely unsuitable, as the intense heat causes them to spread apart and thereby render the interior of the tub unsuitable for enameling.
- The enameling is accomplished in the usual way, and the coating of enamel F when fused onto the interior surface of the metal bath-tub effectually hides all joints and rivets.
- Although I describe in this specification the depressed flange being formed on the central section as the preferable construction, it will be readily understood that I might make the flanges formed at the head and foot sections underlie or overlap the straight ends of the central section. In the latter case of course the inner edge of the head and foot sections might be beveled off so as not to be objectionable.
- What I claim as my invention is—

1. As an improved article of manufacture, a bath-tub composed of a smooth sheet-metal casing made in head, central and foot sections, depressed flanges formed at the ends of the central sections having their surfaces parallel to the cross-sectional contour of the central section and forming a longitudinal extension thereof, the head and foot sections with flanges formed at the inner edge thereof adapted to lie upon the depressed flanges of the central section, means for securing the overlapping sections together so as to form a smooth crackless joint, outwardly-turned flanges formed at the outer edge of the depressed flanges and legs secured to said last-named flanges as and for the purpose specified. 35
2. As an improved article of manufacture, a bath-tub composed of a smooth sheet-metal casing made in head, central and foot sections, inturned flanges formed on the head and foot sections adapted to lie upon the ends 40 of the central sections, means for connecting the sections together, and an inner unbroken lining of enamel or other vitreous material fused over the entire interior surface of the sections and covering the joints as and for the purpose specified. 45
